BATH DRAIN PLUG GUIDE

Robert J. Fife, Delphi, Ind., assignor to
Stephan A. Young, Delphi, Ind.

Application October 3, 1955, Serial No. 538,060

1 Claim. (Cl. 4—199)

This invention relates to bath drains and more particularly to those of the trip lever type.

Trip lever bath drains include a waste $\mathbf{T}$, a waste arm extending horizontally at right angles therefrom and leading to the outlet of a bath tub or the like, a waste outlet and an overflow arm leading vertically from the upper end of the $\mathbf{T}$, a hollow plunger being provided, controlled from a lever at the overflow head and in turn adapted to be positioned so as to close the opening in to the $\mathbf{T}$ to which the waste arm leads, to prevent out flow or water and alternatively to be raised to permit such flow.

One of the serious problems resulting from the above described construction, is that during operation, the plunger which is raised up and down becomes cocked or in some cases wedged in open position so as to render ineffective the lever control provided. While this may be overcome by expensive redesign which makes the drain much more costly, the present invention provides an inexpensive solution to the problem which is equally satisfactory as compared with formerly differently designed products.

The foregoing being the principal object of the invention suggests that a further object is to provide a means which may be incorporated in existing and future bath drains of the trip lever type to prevent the occurrence of the cocking or malfunction as described.

Another object of the invention is to provide a means for the purpose described which may be made of relatively inexpensive material, of simple shape, fool proof function, and assembly and positive action.

Other and further objects of the invention will be understood from a consideration of the specification appended hereto and shown in the drawing wherein:

Figure 1 is a view in elevation, being in section showing a trip lever bath drain with the invention hereof incorporated therein.

Figure 2 is a greatly enlarged cross sectional view fragmentary in nature showing in further detail the invention hereof.

Referring now to the drawing, the type of trip lever bath drain is shown and generally indicated at $\mathbf{A}$ as being mounted upon suitable bath tub shown in fragmentary portion at $\mathbf{B}$, the trip lever bath drain including a waste arm $\mathbf{1}$ connected to the bath tub at the waste outlet indicated at $\mathbf{2}$ as by means of the elbow $\mathbf{3}$ leading to a waste $\mathbf{T}$ $\mathbf{4}$.

The waste $\mathbf{T}$ $\mathbf{4}$ is provided with a suitable threaded opening to which the waste arm $\mathbf{1}$ is connected in a generally conventional manner being shown in enlarged detail in Figure 2 as will be apparent.

Extending upwardly from the waste $\mathbf{T}$ $\mathbf{4}$ is the over flow arm $\mathbf{5}$ at the upper end of which is the head $\mathbf{6}$ suitably connected to the bath tub at the over flow drain portion thereof, the head $\mathbf{6}$ being equipped with an operating handle indicated at $\mathbf{7}$ mounted in a suitable plate indicated in dotted lines at $\mathbf{8}$ so as to be manipulated by the lever portion $\mathbf{9}$ of the said handle $\mathbf{7}$.

The handle $\mathbf{7}$ includes at its inner end and within the head $\mathbf{6}$ a crank portion $\mathbf{10}$ which crank portion is connected to a lift wire $\mathbf{11}$, the lift wire $\mathbf{11}$ in turn having connection with a further lift wire $\mathbf{12}$. At the lower end of the lift wire $\mathbf{12}$ is provided a plunger or stopper member $\mathbf{13}$ of cylindrical form and thus hollow having a portion $\mathbf{15}$ to which the lower end of the lift wire $\mathbf{12}$ is connected. The arrangement thus far described enables the raising and lowering of the plunger $\mathbf{13}$ under control of the handle $\mathbf{7}$ as will be apparent, the plunger $\mathbf{13}$ being equipped at its lower end, more clearly shown in Figure 2 with a suitable seat section $\mathbf{16}$ thereon. The seat section $\mathbf{16}$ described is in turn adapted to engage and seal the outlet portion $\mathbf{17}$ of the $\mathbf{T}$ $\mathbf{4}$, which outlet portion is provided with a seat $\mathbf{18}$ for coaction with the seat portion $\mathbf{16}$ of the plunger $\mathbf{13}$.

The plunger $\mathbf{13}$ is guided by a guide portion $\mathbf{19}$ formed at the upper end of the $\mathbf{T}$ and adjacent the connection of the $\mathbf{T}$ $\mathbf{4}$ with the overflow tube $\mathbf{5}$ previously mentioned. The connection of the over flow tube $\mathbf{5}$ with the $\mathbf{T}$ $\mathbf{4}$ is by means of suitable threads on the said tube $\mathbf{5}$ indicated at $\mathbf{20}$ engaging co-mating threads $\mathbf{21}$ in the upper end of the $\mathbf{T}$ $\mathbf{4}$. This is a generally conventional manner of connecting the respective parts, but in order to prevent the plunger $\mathbf{13}$ from becoming cocked or otherwise functioning improperly, without interfering with relatively easy upward and downward motion which is desirable to effect the shutting off of the waste flow through the outlet $\mathbf{2}$, the invention hereof consists of a guide member indicated at $\mathbf{23}$, in this case being in the form of a tubular element of relatively short length, one end of the tubular element $\mathbf{23}$ being flared as at $\mathbf{24}$ and the other end being flared as at $\mathbf{25}$. It will be understood that the interior diameter of the member $\mathbf{23}$ is substantially the same as or slightly greater than the exterior diameter of the plunger $\mathbf{13}$ so that with the parts in the position of Figure 2 guiding effect is provided by the said member $\mathbf{23}$.

In order to maintain the member $\mathbf{23}$ in position in the desired location to perform the guiding function described, the end $\mathbf{24}$ which is flared as described, is flared to such an extent that the diameter thereof is substantially equal to the external diameter of the over flow tube $\mathbf{5}$ as shown in Figure 2. With the other end of the member $\mathbf{23}$ flared at $\mathbf{25}$ but to a diameter fully substantially equal to or slightly less in extent than the interior diameter of the over flow tube $\mathbf{5}$, the positioning of the member $\mathbf{23}$ will be possible in only one manner, namely with the flared end $\mathbf{24}$ seated on a shoulder $\mathbf{26}$ provided in the upper end of the $\mathbf{T}$ $\mathbf{4}$ and adjacent the inner extremity of the threads so to speak.

With the guide member $\mathbf{23}$ positioned as described, the flared end seated on the shoulder $\mathbf{26}$, the tube $\mathbf{5}$ is engaged as by means of the threads $\mathbf{20}$ previously mentioned with the threads $\mathbf{21}$ and turned to such an extent that the extremity of the tube $\mathbf{5}$ engages the flared portion $\mathbf{24}$ and thus maintains the same in precise aligned position within the tube $\mathbf{5}$. Thereafter by manipulation of the handle $\mathbf{7}$ the plunger $\mathbf{13}$ may be moved upwardly and downwardly so as to cause the seat portion $\mathbf{16}$ thereof to engage the seat $\mathbf{18}$ and thus shut off the flow through the waste arm $\mathbf{1}$ as will be readily understood.

It will thus be seen that there is provided hereby a relatively simple, inexpensive and yet effective guide member for the shut off plunger of a bath drain, which permits free operation of the plunger and yet positively guides the same so as to effect its shut off action.

I claim:

In a bath drain of the class described, in combination, a waste $\mathbf{T}$, a seat at the outlet end thereof, a guide portion at the upper portion, a waste arm comprising a branch of the $\mathbf{T}$ and entering the same intermediate the seat and guide portions, and a hollow plunger shut-off

member movable in the guide portion mentioned, an over-flow tube extending from the guide portion said tube being of greater diameter than the guide portion, said tube being in threaded engagement with the T, and a tubular guide member separate from the plunger positioned within said tube, a shoulder formed in the T adjacent the guide portion, external threads on the tube and internal threads above the shoulder in the T, the tubular guide member having a flared end said flared end being interposed between the end of the tube on which the threads are provided and the shoulder aforesaid, whereby the said guide member is positioned with respect to said tube, the upper end of said tubular guide member

being likewise flared so that the external diameter of said flare is approximately the inner diameter of the tube whereby to further assist in positioning the guide member with respect to said tube.

UNITED STATES PATENT OFFICE
CERTIFICATE OF CORRECTION

Patent No. 2,871,487

February 3, 1959

Robert J. Fife

It is hereby certified that error appears in the above numbered patent requiring correction and that the said Letters Patent should read as corrected below.

In the grant, lines 2 and 11, and in the heading to the printed specification, line 4, name of assignee, for "Stephan A. Young", each occurrence, read -- Stephen A. Young --.

Signed and sealed this 12th day of May 1959.
